UNITED STATES PATENT OFFICE.

JOSEPH C. WOODMAN, OF AUBURN, MAINE, ASSIGNOR TO F. H. & D. BRIGGS & CO., OF SAME PLACE.

SHIRT.

SPECIFICATION forming part of Letters Patent No. 271,180, dated January 23, 1883.

Application filed April 26, 1882. (No model.)

To all whom it may concern:

Be it known that I, JOSEPH C. WOODMAN, of Auburn, in the county of Androscoggin, of the State of Maine, have invented a new and 5 useful Improvement in Woolen Shirts; and I do hereby declare the same to be described in the following specification and represented in the accompanying drawings, of which—

Figure 1 is a front view of a shirt as it appears without its breast-shield. Fig. 2 is a front view, Fig. 3 a rear view, and Fig. 4 a transverse section, of the said breast-shield, which is entirely separable from the shirt, and when in use therewith is fastened on its breast 10 by buttons and button-holes or other suitable separable fastenings. Fig. 5 is a front view, and Fig. 6 a transverse section, of the shirt with its removable breast-shield in place.

The object of my invention is to enable the 20 shirt, provided with a turn-down collar, to be worn either with or without the removable breast-shield, as the wearer may desire. To this end I make the shirt A in the ordinary way, with a turn-down collar and with the 25 opening extending from the collar to or about to the waist, and with the cloth to lap and button together at the opening and collar, such being as represented in Fig. 1 and also in Fig. 6, in which *a* is the opening, *b* and *c* its laps, 30 and *d d d* the buttons for buttoning the outer upon the inner of the said laps. With a shirt so made I combine two other vertical ranges of buttons, *e*, to extend down from the collar to or nearly to the waist, each of such ranges 35 being at an equal or about equal distance from the median vertical line of the front, and one range being on one side and the other being on the opposite side of such line. To these buttons and the bosom of the shirt I apply the 40 removable shield B, which, as represented, is slit vertically down its middle from its upper nearly down to its lower edge, and there provided with a lacing, *f*, going through two ranges of eyelet-holes, *g*, and crossing the slit, 45 such being for ornament, the shield being also embroidered or stitched, if desirable. This removable breast-shield I make with a lining, *h*, in its back, and to form in such lining button-holes *i* without having them go through the 50 shield except at its two upper corners, which,

when the shield is in place in the shirt, are covered by the turned-down collar *k* thereof. These button-holes are to fasten with the buttons *e* the breast-shield to the shirt.

From the above it will be seen that a shirt 55 made with or having a turn-down collar, with a button and button-hole to close it, and also provided with a removable and separate breast-shield, as explained, may be worn either with or without such shield, as the comfort or health 60 of the wearer may require, the shield being an additional protection for the chest during cool weather.

I am aware that shirts have been made double-breasted, or with breast-shields permanently fixed to them; therefore I do not claim 65 such.

I am also aware that a shirt has been made without a bosom, and provided with a detachable front or breast-shield to button to the 70 shirt and cover the breast-opening thereof, such being as represented in the United States Patent No. 46,172, such requiring a person while wearing the shirt to always have the detachable bosom buttoned to it; but with my 75 improved shirt, provided with a permanent bosom and a detachable one, the shirt may be worn either with or without the auxiliary or detachable bosom or breast-shield. Furthermore, the breast-shield, at the middle of its upper edge or part, is not buttoned to the shirt, but there has the lacing tied or knotted, the collar being closed by other means—viz., a button and button-hole. The separable breast-shield, 80 by extending underneath the collar when the latter is turned down, and by having a buttoning-lining, as described, causes the upper end and all the buttons of the shield to be covered when the shield is in place, and thus gives to the shield the appearance of being an 85 integral part of the shirt.

I am also aware of the shirt described in the United States Patent No. 176,935, such shirt having to its front a removable lining or "chest-protector," and such front provided 95 with button-holes to admit of the lining having buttons to be buttoned either on the inner or the outer side of the front, such shirt having no turn-down collar, but simply a neck-band. Consequently I do not claim a shirt 100

made as represented in the said Patents Nos. 46,172 and 176,935.

What I claim as my invention is—

1. The combination of a breast-shield wholly separable from the shirt and provided with a lacing and button-holes therein, as described, with the said shirt provided with a turn-down collar, and having buttons arranged on it (the said shirt) to engage with said button-holes, and also having an opening in its front from the collar to or about to the waist, and such opening provided with laps to button together, as set forth.

2. The combination of a breast-shield wholly separable from a shirt, and provided with a buttoning-lining and button-holes therein, as described, with a shirt having buttons on its front to operate with the said button-holes in holding the shield in place on the shirt-bosom, as set forth, and also having a closing bosom

and collar provided with buttons and button-holes to the laps thereof, all being substantially as specified.

3. The combination of a shirt provided with a turn-down collar and with a closing bosom, open in front from and through the collar to the waist, and having buttons and button-holes for buttoning together the laps of said bosom, and also having two auxiliary ranges of buttons arranged down the front, as described, with a separable or detachable breast-shield, provided with button-holes or a buttoning-lining to button upon the said auxiliary ranges, and also having in it (the said breast-shield) lacing-holes and a lacing, all being substantially as set forth.

JOSEPH C. WOODMAN.
